UNITED STATES PATENT OFFICE.

WILLIAM TAYLOR, OF LEICESTER, ENGLAND.

GRINDING AND POLISHING APPARATUS.

Application filed April 9, 1918. Serial No. 227,563.

To all whom it may concern:

Be it known that I, WILLIAM TAYLOR, a subject of the King of Great Britain, residing at Leicester, England, have invented 5 new and useful Improvements in Grinding and Polishing Apparatus (for which I obtained a patent in Great Britain #1,591, dated Jan. 31, 1917), of which the following is a specification.

10 This invention relates to apparatus for grinding and polishing spherically, or approximately spherically, curved surfaces, particularly the surfaces of lenses, reflectors, and the like, of the kind which comprises 15 two co-acting members, the surfaces of which are respectively convex and concave, and either of which may be the work while the other is the tool, in combination with means for pressing the members together and for 20 varying such pressure, means adapted to move one of the members bodily about the other to effect the rubbing, and means for equalizing the distribution of the rubbing.

In such apparatus it is customary to 25 mount one member, the work or tool, whichever is convex, upon the upper end of a vertical spindle by which it may be rotated, and to move the other (concave) member bodily about the surface of the lower member in order to effect the rubbing or polishing, the 30 orbit on which the upper member moves being generally eccentric to the axis of the lower member. As the upper member moves about the surface of the lower member it rises and falls according to the extent of its 35 movement and the radius of curvature of the sphere; and to effect the bodily motion of the upper member while permitting it to rise and fall in this manner it is customary

40 to move said upper member by means of a ball-pointed vertical finger engaging a hole or socket at about the centre of said upper member, this finger being fixed at the free end of an arm which is pivoted about a horizontal axis, so that the finger may rise and fall, and is adapted to be moved in a path which may be circular in plan view, so as to effect the bodily motion of the member, by 45 means of a crank or its equivalent. Pressure is put on the pivoted arm and finger in order to press the tool and work together. For the best class of work the uniformity of such pressure is of great importance. I 50 find, however, that owing to the inertia of the finger and arm which actuate the upper member, their rising and falling result in

variations of pressure; and further variations occur because the finger does not rise and fall, nor press the upper member, in the direction of the centre of the sphere, but in a 60 direction more or less tangential to the surface thereof. Furthermore, owing to the fact that, although the pivoted arm may move the upper member and the finger with constant velocity in a path which is circular 65 in plan view, their rising and falling causes the upper member to follow a more or less elliptical path on the surface of the lower member, with the result that the velocity varies at different parts of the last-mentioned path and the accuracy of the grinding or polishing is thereby affected.

According to the present invention I employ a pair of rotary driving spindles for actuating the respective co-acting members, 70 said spindles having their axes of rotation mutually inclined in the same plane and mutually intersecting at substantially the common centre of curvature of the surfaces 75 of the co-acting members. For the sake of convenience, this centre is hereinafter termed the "principal centre" of the apparatus. The one member, hereinafter termed the "concentric member", is mounted upon its spindle concentrically (i. e., with the axis of rotation of the spindle passing through the centre of curvature and approximately through the centre of the surface of said member); whilst the other member, hereinafter termed the "eccentric member", is attached to its 80 spindle eccentrically so as to be adapted for being moved thereby bodily (and its centre of surface at substantially constant velocity) 85 on and about the surface of the concentric member.

The invention includes other features of construction and arrangement of parts, all as hereinafter described and specifically pointed out in the claims.

It will be perceived that the action of apparatus constructed in accordance with the present invention differs materially from that of known apparatus in which the work and the tool are respectively mounted 100 concentrically upon rotary driving spindles the axes of which are mutually incl'ned in one plane and intersect one another at the centre of curvature of the work, the work being fed positively (i. e. with a pressure wh'ch is not yielding or elastic), 105 in the direction of its own axis, against the edge of a rotating disc which constitutes 110

the tool, each point in the grinding edge of which follows a circular path the position of which relatively to the work remains constant, so that the tool itself has no bodily movement on or about the surface of the work.

In the accompanying drawings, which illustrate a convenient form of apparatus constructed in accordance with the invention, the machine comprising four units arranged side by side, Figure 1 is a vertical section of the machine from front to back, the section being taken on the plane in which the axes of the two spindles of the pair comprised in one unit both lie; Figure 2 is a front elevation of the machine, drawn to a smaller scale, the spindles of both groups being shewn for convenience in one plane; Figure 3 is a view similar to Figure 1, shewing the right hand side of the machine in elevation; and Figure 4 is a view similar to Figure 3 but on a smaller scale and illustrating a construction in which the spindle-carrying frame is formed in two sections pivoted together to provide for varying the angular relation of the upper and lower spindles.

For the sake of more ready identification, that spindle which, in each unit comprised in the example illustrated, actuates the so-called concentric member will be referred to as the "lower spindle", and that spindle which actuates the so-called eccentric member will be referred to as the "upper spindle"; such being the generally preferable arrangement shewn in the drawings.

In each pair of rotary driving spindles, $x-x$ is the axis of the lower spindle A and $y-y$ the axis of the upper spindle B, the spindle A being vertical whilst the spindle B, which is on a higher lever, is inclined so that its axis $y-y$ intersects the axis $x-x$ in the point z . The axes of the lower spindles A of the several units extend in one plane, and those of the upper spindles B of the several units likewise extend in one plane. In Figure 2, for the sake of convenience, the frame C of the machine is shewn as broken and the axes $y-y$ of the several upper spindles B are shewn as if extending in a vertical plane instead of at an inclination to the vertical. In each unit shewn in Figure 2, the "concentric" member mounted on the lower spindle A is omitted, as is also the "eccentric" member and the means whereby the same is attached to the upper spindle B.

Referring more particularly to the single unit seen in Figure 1, the concentric member D is shewn as convex and hemispherical, and as serving to carry a number of convex lenses d which are embedded in a coating of cement adherent to the convex surface of the member, the centre of curvature of the member as a whole being at the point z

(i. e., the so-called principal centre) whereat the axes $x-x$ and $y-y$ intersect one another. The concentric member D is removably attached to the spindle A through the medium of a supplementary spindle E which may be integral with the member D itself and which is caused to extend in axial alignment with the spindle A by resting in a chuck or socket e fast on said spindle; the contiguous ends of the spindle A and supplementary spindle E being cut away obliquely as at e^1 so as to become tightly keyed together when the supplementary spindle is dropped into the socket e . A number of concentric members D having various radii of curvature would as a rule be used interchangeably; the effective length of the supplementary spindle E being in each case such as to ensure substantial coincidence of the centre of curvature of the member D with the "principal centre" z . In order, however, to enable perfect coincidence to be established, the position of the spindle A lengthwise of its axis may be made adjustable at will; for which purpose, in the example illustrated, the spindle A, which is adapted to slide through its upper and lower bearing f^1 , f^2 in the frame C, rests upon a footstep bearing f carried by a stirrup F which is suspended from a forwardly-extending horizontal shaft G journalled in a bearing g^1 in the frame C, the outer or front end of the shaft G having a crank handle g^2 whereby it may be turned to raise or lower the footstep bearing f . The spindle A is shewn as carrying, between the bearings f^1 , f^2 , a worm wheel H^1 in mesh with a worm H^2 on a horizontal shaft H which serves in common for driving the lower spindles A of all the units comprised in the machine.

The grinding or polishing member J which, in the example illustrated, constitutes the so-called eccentric member, and which is shewn as concave and approximately hemispherical, is so connected with the upper spindle B as to be caused by the revolution of the latter to move bodily in a circular path, and the centre of its surface at constant velocity, over the surface of the work carried by the spindle A, the attachment between the eccentric member J and spindle B being effected at a ball-and-socket joint whereof the ball j is eccentric to the axis $y-y$ of the spindle B so as to revolve around said axis in a path all points of which are at the same distance from the principal centre z . There will thus be no movement of the ball j longitudinally of the axis of the spindle. The ball j is on the lower end of a rod or finger j^1 which, extending radially of the principal centre z , is slidably axially through, and clamped by means of a screw j^2 in, a bearing at the free end of a pivoted

or hinged arm K, so that the distance of the centre of the ball j from the principal centre z may be permanently adjusted at will to suit eccentric members J of different 5 curvatures and to change correspondingly the radius of the orbit of the ball j , that is, to obtain correspondingly differing and proportionate eccentricities of the ball j relatively to the axis $y-y$. The arm K is pivoted at an axis k to a bracket L carried by 10 a crank arm M fast on the spindle B, the axis k lying in a plane perpendicular to the axis of said spindle, so that the ball j and member J are capable of bodily movement in a direction substantially towards and from 15 the principal centre z , whilst the member J is free to accommodate its surface contour to that of the work by movement in any direction about the ball j .

20 In order to cause the member J to exert the requisite pressure upon the work, a spring N is interposed between the arm K and bracket L; this spring, which is housed, and takes its abutment, within a tubular 25 casing n pivoted at n^1 to the arm K, acts against a plunger n^2 which bears against a concave circular segment l on the bracket L concentric with the axis n^1 . Hence, by moving the casing n about the axis n^1 , the distance 30 from the axis k at which the spring N acts upon the arm K, and, therefore the pressure exerted by the member J, may be varied without altering the stress existing in the spring itself.

35 The bracket L might be a fixture on the crank arm M, but in the example illustrated is shewn as pivoted thereto at an axis m which extends parallel to the axis $y-y$ so as to intersect the axis k perpendicularly; 40 this arrangement permitting of the arm K being swung aside (when the machine is at rest) to facilitate removal of the member J or member D when necessary. The arrangement also affords means for varying the eccentricity of the ball j relatively to the axis $y-y$ without substantially altering the distance of the ball from the principal centre z ; 45 for which purpose a set-screw O which passes through a threaded hole in a lug opposite to the crank arm M is adapted, in the 50 revolution of the spindle B and crank arm M, to bear against a lug o on the arm K, the adjustment of the screw O serving to determine the angular position of the arm K about the axis m and, consequently, the eccentricity of the ball j relatively to the axis $y-y$.

55 The spindle B is journalled in upper and lower bearings b^1 , b^2 in the frame C, between which bearings it carries a worm 60 wheel P^1 in mesh with a worm P^2 on a horizontal shaft P parallel with the shaft H; the shaft P serving in common for driving the upper spindles B of all the units comprised in the machine. In Figs. 1 and 3 the

angular position of the upper spindle B relatively to the lower spindle A is shewn as fixed, but it might be made variable, as illustrated by Fig. 4, for example, by dividing the frame C into two sections C^1 and C^2 70 hinged together about a horizontal axis passing through the principal centres z of all the units, suitable means being provided for clamping the two sections together after adjustment about said axis. 75

The improved apparatus is adapted for producing accurate surfaces corresponding to as much as a hemisphere, and is most economically used upon lenses, or blocks of lenses, of substantially hemispherical form. 80 For this purpose I find that good results are produced when the angle w between the axes $x-x$ and $y-y$ (measured in their common plane) is made about 20° , and when the angle between the axis of the rod j^1 and the axis $y-y$ (measured in their common plane) is also made about 20° . 85

The spindle which carries the work (in the example illustrated, the lower spindle A) is preferably rotated more slowly than the spindle which carries the tool (in the example illustrated, the upper spindle B), and in the drawings, the shaft H whereby all the lower spindles A are actuated is shewn as driven from the shaft P whereby all the upper spindles B are actuated, a belt passing for this purpose around a relatively small pulley p on the shaft P and a relatively large pulley h on the shaft H. 90 The shaft P itself may be driven from any convenient source of power (such as, e. g., a shaft—not shewn—extending beneath the machine parallel to the shaft P) by means, for example, of a belt Q passing around a pulley q on said shaft; starting and stopping means being provided such as a jockey pulley r adapted to bear against the belt and mounted upon one arm of a lever R fulcrumed to the frame C at r^1 , the other arm of this lever being coupled by a link s to the lever S which is fulcrumed to the frame C at s^1 and controlled by a slideable hand-lever T. 95

U is a drip tray extending between the end members of the frame C and adapted to receive the drip from the work and tool in each unit comprised in the machine. All the lower spindles A pass through the bottom u of the drip tray, which serves to carry the upper bearings f^1 of all of said spindles, and which is inclined from each end toward a central discharge orifice u^1 . Suitable provision is made for excluding dust or grit from the various bearings, and for lubricating the several working parts. 110

Having now particularly described and ascertained the nature of my said invention and what manner the same is to be performed, I declare that what I claim is:—

1. Apparatus for grinding and polishing 130

- spherically curved surfaces, comprising a pair of co-acting work and tool members, one having a convex and the other a concave surface, means for imparting a concentric 5 rotary movement to one of said members, means for moving the other of said members bodily in a circular path about an axis which intersects the axis of rotation of the first said member substantially at the common 10 center of curvature of the surfaces of the two co-acting members, and means for applying to the member which is moved bodily a force in a direction at an angle to the axis of the movement of said member and substantially toward the center of curvature 15 of the co-acting member.

2. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving 20 spindle, and the other of said members being connected to its driving spindle eccentrically, and means for exerting constant pressure on the eccentric member in the direction at an angle to the axis of its spindle and substantially toward the point of intersection 25 of the axes of the driving spindles.

3. Apparatus for grinding and polishing spherically curved surfaces, comprising a pair of coacting work and tool members, one having a convex and the other a concave surface, means for imparting a concentric rotary movement to one of said members, and means for moving the other of said members bodily in an eccentric path on and about the surface of the first mentioned member, said moving means including a device adapted to engage and move the said member and being adjustable along a line radial to the common center of curvature 30 of the two coacting members.

4. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving 35 spindle, and means for causing the other of said members to be moved by its driving spindle bodily in a circular path on and about the surface of the first mentioned member, said means comprising a crank arm on the spindle, a crank pin adapted to engage and move the member, said crank pin being mounted to be swung laterally about an axis offset from the axis of the spindle to vary the radius of its orbit, and adjustable means for determining the lateral position of the crank pin when the apparatus is in operation.

5. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving 40 spindle, and a crank arm on the spindle, and a crank pin adapted to engage and move the member, said crank pin being adjustable substantially in a direction toward or from the point of intersection of the axes of the driving spindles.

6. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and means for causing the other of said members to be moved by its driving spindle bodily in a circular path on and about the surface of the first mentioned member, said means comprising a crank arm on the spindle, and a crank pin adapted to engage and move the member, said crank pin being mounted to be movable laterally to facilitate access to or removal of either of the two co-acting members.

7. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and means for causing the other of said members to be moved by its driving spindle bodily in a circular path on and about the surface of the first mentioned member, said means comprising a crank arm on the spindle, a crank pin adapted to engage and move the member, said crank pin being mounted to be swung laterally about an axis offset from the axis of the spindle to vary the radius of its orbit, and adjustable means for determining the lateral position of the crank pin when the apparatus is in operation.

spindle, and means for causing the other of said members to be moved by its driving spindle bodily in a circular path on and about the surface of the first mentioned member, said means comprising a crank arm on the spindle, a hinged arm carried by said crank arm and provided with means eccentric to the axis of said spindle for engaging and moving said member, a spring tending to move said arm about its hinge to press said member in the direction toward the point of intersection of the axes of the spindles, and means for adjusting the pressure exerted on said member by varying the radial distance from the hinge at which said spring acts.

8. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and means for causing the other of said members to be moved by its driving spindle bodily in a circular path on and about the surface of the first mentioned member, said means comprising a crank arm on the spindle, an arm pivotally mounted on the crank arm to swing about an axis parallel to the axis of the spindle and provided at its free end with a member engaging part, said pivoted arm being free to swing in one direction out of operative position to facilitate access to or removal of the co-acting members, and a stop for limiting the movement of said pivoted arm in the other direction, said stop being adjustable for varying the radius of the orbit of the member engaging part carried by said pivoted arm.

9. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and the other of said members being connected to its driving spindle eccentrically so as to be moved thereby bodily in a circular path on and about the surface of the first-mentioned member, and means for adjusting the position of the co-acting members to cause the common center of

curvature of the surfaces of the two members to coincide with the point of intersection of the axes of the spindles.

10. Apparatus for grinding and polishing spherically curved surfaces, comprising a pair of co-acting work and tool members, one having a convex and the other a concave surface, and a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and the other of said members being connected to its driving spindle eccentrically so as to be moved thereby bodily in a circular path on and about the surface of the first-mentioned member, the spindle carrying the concentric member being adjustable lengthwise for bringing the center of curvature of the member carried thereby into position to coincide with the point of intersection of the axes of the spindles.

11. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, an engaging device carried eccentrically by the other spindle for engaging the other of said members to move the same, said engaging device being adjustable in a direction toward and from the point of intersection of the axes of the spindles to suit co-acting members of less or greater curvature and to proportionately diminish or increase the radius of its orbit, and means for changing the radius of the orbit of said engaging device without substantially altering the distance of said device from said point of intersection of the axes of the spindles.

12. Apparatus for grinding and polishing spherically curved surfaces, comprising a pair of co-acting work and tool members, one having a convex and the other a concave surface, a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and an engaging device

carried eccentrically by the other spindle for engaging the other of said members to move the same bodily in a circular path on and about the surface of the first-mentioned member, said engaging device being adjustable in a direction toward and from the point of intersection of the axes of the spindles, and the spindle carrying the concentric member being adjustable lengthwise for bringing the center of curvature of the member carried thereby into position to coincide with the point of intersection of the axes of the spindles.

13. Apparatus for grinding and polishing spherically curved surfaces, comprising a pair of co-acting work and tool members, one having a convex and the other a concave surface, and a pair of rotary driving spindles for actuating said co-acting members, said spindles having their axes of rotation mutually inclined in the same plane and intersecting at substantially the common center of curvature of the surfaces of the co-acting members, one of said co-acting members being mounted concentrically on its driving spindle, and the other of said members being connected to its driving spindle eccentrically so as to be moved thereby bodily in a circular path on and about the surface of the first-mentioned member, the spindle carrying the concentrically mounted member being provided with a socket, and the member carried thereby having a stem to extend into said socket, the length of said stem being proportioned according to the curvature of the surface of the member to cause the center of curvature of the surface of the member to be located at the point of intersection of the axes of the spindles.

14. Apparatus for grinding and polishing spherically curved surfaces, comprising means for driving a pair of co-acting work and tool members, one having a convex and the other a concave surface, said means including a rotary driving spindle, a crank arm on said spindle, a second arm carried by said crank arm and connected thereto by means permitting it to swing about an axis in a plane perpendicular to the spindle, an engaging device for engaging and moving one of said co-acting members carried by said second arm at a point which is eccentric to the spindle axis and normally on the opposite side of the spindle axis from the point of pivotal connection of said second arm to the crank arm, a spring tending to move said crank arm to press the engaging device in the direction toward the center of curvature of the surfaces of the co-acting members, said second arm also being mounted to swing transversely to the axis of the spindle to carry said engaging device away from its operative position, and means for holding said second arm against such trans-

verse movement to maintain said engaging device in operative position, said means being adjustable for varying the operative position of said second arm to vary the radius of the orbit of the engaging device. 70

15. Apparatus for grinding and polishing spherically curved surfaces, comprising a pair of co-acting work and tool members, one having a convex and the other a concave surface, and a pair of rotary driving spindles for actuating said co-acting members, said spindles having their axes mutually inclined in the same plane and intersecting at substantially the common center of curvature of the surfaces of the co-acting members, one of said spindles being mounted so that it may be swung about an axis which extends substantially perpendicular to the plane of the axes of the spindles and passes substantially through the point of intersection of the axes of the spindles, one of said co-acting members being mounted concentrically on its driving spindle, and the other of said members being connected to its driving spindle eccentrically. 80 85 90

16. A multiple unit machine for grinding and polishing spherically curved surfaces, comprising a plurality of pairs of rotary driving spindles for actuating a plurality of pairs of co-acting work and tool members, the spindles of each pair having their axes of rotation mutually inclined in the same plane and intersecting at substantially the common center of curvature of the surfaces of the pair of co-acting members actuated thereby, and the points of intersection of the axes of the several pairs of spindles being alined, and means for simultaneously varying the inclination of the axes of all the pairs of spindles by movement of the corresponding spindles of each pair about an axis which passes through the point of intersection of the axes of the spindles. 100 105 110

17. Apparatus for grinding and polishing spherically curved surfaces, comprising a pair of coacting work and tool members one having a convex and the other a concave surface; means for imparting a concentric rotary movement to one of said members; and moving means for the other of said members, including an element constrained independently of the contact between said members to move in a circle, whose axis is inclined to the axis of rotation of the first said member and intersects said axis substantially at the common center of curvature of the coacting spherical surfaces of said members, an element engaging said second member, and a spring coacting between said elements to press said second member against said first member. 115 120 125

18. Apparatus for grinding and polishing spherically curved surfaces, comprising a pair of coacting work and tool members, one

- having a convex and the other a concave surface; means for imparting a concentric rotary movement to one of said members; and moving means for the other of said members, including an element constrained to move in a circle whose axis intersects the axis of rotation of the first member substantially at the common center of curvature of the surfaces of the two coacting members, 5 an element engaging said second member and mounted to revolve with said first mentioned element and so as to be free to move with respect thereto substantially towards and from the common center of curvature 15 of the surfaces of the two coacting members, and a spring coacting between said elements to press said second member against said first member.
19. Apparatus for grinding and polishing spherically curved surfaces, comprising a pair of coacting work and tool members, one having a convex and the other a concave surface; means for imparting a concentric rotary movement to the convex member; means for moving the concave member bodily in a circular path, said means including an element constrained independently of the contact between said members to move in a circle whose axis intersects the axis of rotation of the convex member at an acute angle and substantially at the common center of curvature of the surfaces of the two coacting members, and a connection 25 between said element and the concave member; and means arranged to press the two coacting members together with a force which remains constant throughout the circular movement of the second mentioned member.
20. Apparatus for grinding and polishing spherically curved surfaces, comprising a pair of coacting work and tool members, one having a convex and the other a concave surface, a pair of rotary driving spindles for actuating said coacting members, said spindles having their axes of rotation mutually inclined and intersecting at a fixed point, one of said members being mounted concentrically on its driving spindle and the other of said members being connected to its driving spindle eccentrically, and means for adjusting the position of the coacting members longitudinally of one of the spindles to cause the common center of curvature of the surfaces of the two members to coincide with the point of intersection of the axes of the spindles.
21. Apparatus for grinding and polishing spherically curved surfaces, comprising a pair of coacting work and tool members, one having a convex and the other a concave surface, a pair of rotary driving spindles for actuating said coacting members, said spindles having their axes of rotation 60 mutually inclined and intersecting at a fixed point, one of said co-acting members being mounted concentrically on its spindle and the other of said members being connected to its driving spindle eccentrically, the spindle carrying the concentric member being adjustable lengthwise for bringing the center of curvature of the member carried thereby into position to coincide with the point of intersection of the axes of the spindles.
22. Apparatus for grinding and polishing spherically curved surfaces, comprising a pair of co-acting work and tool members, one having a convex and the other a concave surface, a pair of rotary driving spindles 65 for actuating said co-acting members, said spindles having their axes of rotation mutually inclined and intersecting at a fixed point, one of said co-acting members being mounted concentrically on its driving spindle, and an engaging device carried eccentrically by the other spindle for engaging the other of said members to move the same, said engaging device being adjustable in a direction toward and from the point of intersection of the axes of the spindles, and the spindle carrying the concentric member being adjustable lengthwise for bringing the center of curvature of the member carried thereby into position to coincide with the point of intersection of the axes of the spindles.
23. Apparatus for grinding and polishing spherically curved surfaces, comprising a pair of co-acting work and tool members, one having a convex and the other a concave surface, and a pair of rotary driving spindles for actuating said co-acting members, said spindles having their axes of rotation 70 mutually inclined and intersecting at a fixed point, one of said co-acting members being mounted concentrically on its driving spindle and the other of said members being connected to its driving spindle eccentrically, the spindle carrying the concentrically mounted member being provided with a socket and the member carried thereby having a stem to extend into said socket, the length of said stem being proportioned according to the curvature of the surface of the member to cause the center of curvature of the surface of the member to be located at the point of intersection of the axes of the spindles.
24. Apparatus for grinding and polishing spherically curved surfaces, comprising a frame, a pair of opposed spindles mounted on said frame and constrained thereby so that their axes intersect at a fixed point, a pair of co-acting work and tool members, one having a convex and the other a concave surface, a stem on which one of said members is concentrically mounted, means for securing the other end of said stem to the end of one of said spindles, the length 75

- of the stem being proportioned according to the curvature of the surface of the member to cause the center of curvature of said surface to be located at the point of intersection of the axes of the spindles, the other of said co-acting members being connected to its driving spindle eccentrically.
25. Apparatus for grinding and polishing spherically curved surfaces, comprising a
- 10 pair of rotary driving spindles having their axes mutually inclined in a common plane, one of said spindles being angularly adjustable about an axis perpendicular to said common plane and passing through the
- 15 point of intersection of the spindle axes, and a pair of co-acting work and tool members, one having a convex and the other a concave surface and mounted on said spindles relatively with the common center of curvature of their surfaces substantially at the point of intersection of the spindle axes, one of said co-acting members being mounted concentrically on its driving spindle and the other of said members being connected
- 20 to its driving spindle eccentrically.
- 25 to its driving spindle eccentrically.

26. A grinding and polishing machine, including a pair of opposed spindles having their axes mutually inclined in a common plane, one of said spindles being angularly adjustable with respect to the other about an axis perpendicular to said plane and passing through the point of intersection of the spindle axes, and having an offset crank pin.

27. A lens grinding and polishing machine, including a pair of opposed spindles, one of said spindles being angularly adjustable with respect to the other and having a crank, and a pin mounted on said crank so as to be adjustable towards and from the point of intersection of the spindle axes.

28. A lens polishing machine, including a pair of opposed spindles mutually inclined in the common plane, a crank on one of said spindles, and a pin on said crank adjustable towards and away from the point of intersection of the axes of said spindles.

WILLIAM TAYLOR.
